(57) **CLAIM**

The ornamental design for a nasal strip breathing aid as shown and described.

DESCRIPTION

FIG. 1 is a top perspective view of a first embodiment of a nasal strip breathing aid;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof;

FIG. 7 is a right side elevation view thereof;

FIG. 8 is a top perspective view of a second embodiment of a nasal strip breathing aid;

FIG. 9 is a top plan view thereof;

FIG. 10 is a bottom plan view thereof;

FIG. 11 is a rear elevation view thereof;

FIG. 12 is a front elevation view thereof;

FIG. 13 is a left side elevation view thereof; and,

FIG. 14 is a right side elevation view thereof.

The broken lines illustrate portions of the nasal strip breathing aid that form no part of the claimed design.

1 Claim, 14 Drawing Sheets
